UNITED STATES PATENT OFFICE.

JOHN B. AUFULDISH, OF DAYTON, OHIO.

STARTER FOR EXPLOSIVE-ENGINES.

1,155,781.

Specification of Letters Patent.

Patented Oct. 5, 1915.

Application filed May 20, 1912. Serial No. 698,390.

To all whom it may concern:

Be it known that I, JOHN B. AUFULDISH, a citizen of the United States, residing at Dayton, in the county of Montgomery and State of Ohio, have invented certain new and useful Improvements in Starters for Explosive-Engines, of which the following is a specification, reference being had therein to the accompanying drawing.

- 10 This invention relates to starters for explosive engines and more particularly to that type of starter which injects a charge of explosive gas, such as acetylene gas, into the cylinder of the engine under such conditions that it may be exploded to impart movement to the piston. In starters of this type much difficulty has been experienced in successfully confining the gas, particularly when acetylene gas is used, it having been found that it is very difficult to so construct the valves that there will be no leakage of gas about the same. Especially is this true of the throttle valve which controls the communication between the gas tank 20 and the distributer. No matter how finely this valve is ground it happens almost invariably that after having been in use a short time it will permit the escape of the gas.
- 25 The primary object of the present invention is to provide a distributer having a valve so constructed and arranged that it will effectually confine the gas and prevent any leakage in the connection between the source of supply and the distributer.

To this end it is a further object of the invention to provide, in a starter of this character, a valve operating mechanism, the movement of which in one direction will be limited by the seating of the valve and which will be so constructed that any wear on the valve will be automatically taken up by the action of the operating mechanism; and further, to provide such a mechanism 40 in which the seating of the throttle valve will also control the movement of the distributing valve.

In the accompanying drawings, Figure 1 is a longitudinal section taken centrally through a starter embodying my invention. Fig. 2 is a similar view taken centrally through a starter of a different construction, which also embodies my invention. Fig. 3 is a longitudinal section of the device illustrated in Fig. 1, part of the valves open and a part closed. Fig. 4 is a section taken on

the line $x-x$ of Fig. 3, looking in the direction of the arrows and Fig. 5 is a detail view of the operating handle and indicator dial.

In these drawings I have illustrated one embodiment of my invention, the essential characteristics of the invention being the same in both forms here shown. In each instance the starter comprises a casing 1, comprising a distributer and having mounted therein a distributing valve or valves. In each instance the casing is connected with the source of gas supply, such as the well-known Prest-o-lite tank, by means of a port 2 formed in the casing and connected with the pipe leading to the tank by means of a nipple 3. In both forms of the device here shown, the port 2 is arranged substantially in the center of one end of the casing, which is cylindrical in shape, and is provided with a tapered valve seat 4, adapted to receive the tapered valve 5, which in the present instance is in the form of a heavy needle valve. This valve fits snugly in the tapered valve seat 4, with its point extending beyond the valve seat into the port 2, and consequently the tapered surface of the valve engages the entire surface of the valve seat and neither the valve nor the valve seat will be roughened or have shoulders worn therein by the seating action. The valve may be actuated in any suitable manner but I prefer to provide an operating mechanism in which a screw device is provided to move the valve 5 on to and off of its seat. In the present construction a collar 6 is supported in alignment with the valve seat and is provided with internal screw threads. This collar is here shown as supported from the side wall of the casing and as having that end adjacent to the port 2 spaced away from the end of the casing to permit the free passage of the gas from the port to the interior of the casing. The stem 7 of the valve 5 is screw-threaded to co-operate with the screw-threaded collar 6 and consequently the rotation of the valve stem 7 will cause the valve to move toward or away from its seat. Any suitable means may be provided for rotating the valve stem to cause the valve to be moved with relation to its valve seat. In Fig. 1 I have shown this device as comprising a handle 8 secured to one end of a shaft 9 which extends through the casing 1 and through the supporting structure for the starter which, in the present instance, is shown as the dash board 10 of an automo-

bile. The shaft 9 is connected with the stem 7 of the throttle valve 5 in such a manner as to cause the valve stem to rotate with the shaft but to permit the stem to have longitudinal movement relatively to the shaft, which is preferably held against longitudinal movement. This may be accomplished by providing the end of the valve stem with a socket 11 to receive the end of the shaft 9 and having laterally extending projections 12 to receive lugs 13 secured to the end of the shaft. These lugs fit loosely within the lateral extensions of the projections of the socket and while they cause the two parts to 15 rotate in unison they permit the stem to move longitudinally relatively to the shaft.

The particular starter shown in Fig. 1 is provided with a series of pockets 14 to receive and store the gas. These pockets are 20 divided from that end of the casing in which the valve 5 is mounted by a transverse partition 15 having therein a valve seat 16 provided with a series of ports, one for each storage chamber or pocket 14. A 25 valve member 17 is mounted in said valve seat and provided with ports adapted to be moved into and out of registration with the ports in the valve seats to control the flow of gas to the respective pockets 14. The 30 valve 17 is preferably actuated from a handle 8 and to this end has therein slots 18 arranged on opposite sides of the central opening through which the shaft 9 passes. A pin 19 extends through the shaft and projects beyond both sides thereof into the slots 18, thus causing the valve member to rotate in unison with the shaft 9. Each pocket 14 is connected with one of the cylinders by means of a suitable conduit 20 and the flow 40 of gas through each conduit is controlled by means of a rotary plug valve 21. These valves are also preferably actuated by the movement of the handle 8 and to this end are each provided with a stem 22, having 45 therein a gear 23 adapted to mesh with the central gear 24 secured to the shaft 9. It will be noted, therefore, that all the valves of the device are actuated by a single movement of the handle 8. The valve 17 may be 50 so adjusted with relation to the shaft 9 that it will be opened, or closed, as may be desired, when the throttle valve is opened and the rotary plug valves 21 may also be adjusted so as to admit the gas simultaneously 55 to the cylinders, or successively. Preferably, a suitable stop, such as a pin 25, is provided in the path of the handle 8 to so limit its movement in one direction that the ports of the distributing valves will be in proper 60 alignment with their conduits, to connect their pockets to the cylinders. Preferably, when the pockets are connected with the cylinder the valve 17 will be closed so that communication between the pockets, and consequently, between the cylinder, and the source

of supply, will be interrupted. The return movement of the handle closes the valve 21 and the valve 17 and seats the throttle valve 5. The closing movement of the handle is limited only by the seating of the valve 5, 75 consequently this valve will always be moved into snug engagement with its seat and any wear on the seat or valve will be automatically taken up. It will be noted in this connection that the first movement of the handle 75 to unseat the throttle valve does not open either the intermediate valve 17 or the distributing valves 21. By the time the valve 17 has been rotated far enough to open the ports therein the throttle valve will have 80 been unseated a distance sufficient to permit of a strong flow of gas past the same into the pockets 14. The distributing valves 21 being closed, the gas is not yet admitted to the cylinders of the engine. The continued 85 movement of the operating handle serves to further open the throttle valve but closes the intermediate valve 17 and opens the distributing valves 21, thus placing the several pockets 14 in communication with the respective cylinders of the engine and interrupting their communication with the source of supply. Where the pressure at the source of supply is reasonably strong, the operating handle may be moved continuously from one 90 position to another and the brief period during which the intermediate valve will be open will be ample to charge the pockets 14. However, if the pressure at the source of supply should be low, the handle may be 100 allowed to dwell for an instant in the position in which the intermediate valve is open, thus allowing ample time for the gas to pass into the pockets. An indicator dial 37 is mounted on the supporting structure for the 105 device and so arranged that the handle travels over the same. This dial is provided with a suitable indication to enable the operator to know when the intermediate valve is open. Upon the return movement of the 110 handle the distributing valve will be closed before the intermediate valve is opened. The opening of the intermediate valve on the return movement will cause the pockets to be charged upon the return stroke and this charge will be sufficient to again operate the starter, provided the start is made within a reasonable time. This charge, 115 which enters the pockets on the return stroke of the handle, is not necessary, however, as a charge will always enter the pockets during the first portion of the forward movement of the handle. By the time the throttle valve is fully seated, not only the distributing valves but the intermediate valve 120 are closed. This arrangement enables a further use of the starter. That is, the source of gas supply for the starter can be used as a source of supply for the continued operation of the engine, if it should be desired, in 125 130

case of emergency. To permit this use of the starter, that portion of the interior of the casing between the partition 15 and the end wall is provided with an outlet 38 which is connected by a nipple with a pipe leading 5 to the intake manifold of the engine. This connection between the gas and the intake manifold is normally closed by means of a valve or otherwise. When it is desired to 10 operate the engine from this source of supply, communication is provided between the outlet 38 and the intake manifold of the engine and the handle of the starter is moved far enough to open the throttle valve without opening the intermediate valve 17. The 15 amount of movement which is required to open the intermediate valve 17 is such that the throttle valve can be opened a distance to permit an ample flow of gas without opening the intermediate valve. The indicator dial may be provided with a suitable 20 marking, such as the word "Intake," to indicate the proper position of the handle. Further the dial is provided with graduations so that the extent of the opening of 25 the throttle valve may be regulated.

In Fig. 2 I have shown a slightly different form of distributing valve. As here shown the casing is provided with a recess having 30 tapered walls, as indicated at 26, which form a seat for a tapered valve member 27, which is hollow and communicates with the interior of the casing 1 by means of ports 28 and has other ports 29 adapted to register 35 with conduits 30 in the casing to connect the interior of the valve member 27 with the cylinders of the engine. This valve member is provided with a forwardly projecting portion 31 having a non-cylindrical socket 40 32 to receive the non-cylindrical end portion 33 of the valve stem 27, thus causing the two parts to rotate together and permitting them to have longitudinal relative movement. The valve member 27 may be actuated in 45 any suitable manner but is here shown as having a stem 34 on which is mounted a pinion 35 which meshes with a rack 36. The rack is conveniently arranged for operation. Inasmuch as this operating mechanism does 50 not form a part of this invention it is not necessary that it should be shown and described in detail.

While I have shown and described one 55 form of the invention, it will be understood that this form is chosen for the purpose of illustration only and that I do not wish to be limited to the details of construction shown and described, as obvious modifications will occur to one skilled in the art. For example, 60 it will be understood that while I have shown and described a complete screw-thread for actuating the tapered valve, substantially the same results can be secured by providing the valve stem and its support 65 with co-operating inclined parts of any kind,

arranged to impart longitudinal movement to the valve when the same is rotated.

Having fully described my invention, what I claim as new and desire to secure by Letters Patent, is:—

1. A device of the character described comprising a casing having a chamber provided with an inlet port communicating with a source of gas supply, said port having a valve seat at its inner end, a screw-operated 70 valve mounted for movement toward and away from said valve seat, a distributor communicating with said chamber, and means for operating said distributor and said valve in unison.

2. A device of the character described comprising a casing having a chamber provided with an inlet port communicating with a source of gas supply, said port having a valve seat at its inner end, a screw-operated 75 valve mounted for movement toward and away from said valve seat, a distributor communicating with said chamber, and means for operating said distributor and said valve in unison said means being so 80 arranged that the movement of both the distributor and the valve in one direction will be limited by the seating of said valve.

3. A device of the character described comprising a casing having a chamber provided 95 with an inlet port communicating with a source of gas supply, a screw-actuated valve to control the flow of fluid through said inlet port, said chamber also having an outlet, means for controlling the escape of gas 100 through said outlet, and a single actuating device for imparting movement to said valve and to said controlling means.

4. A device of the character described comprising a casing having a chamber provided 105 with an inlet port communicating with a source of gas supply, a valve to control the flow of fluid through said inlet port, a screw-threaded actuating device for said valve arranged within said chamber, said chamber 110 also having an outlet, means for controlling the escape of gas through said outlet, and means for causing said valve and said controlling means to move in unison.

5. A device of the character described comprising a casing having a chamber provided with an inlet port communicating with a source of gas supply, a valve to control the flow of fluid through said inlet port, a screw-threaded actuating device for said 120 valve arranged within said chamber, said chamber also having an outlet, means to control said outlet, and means for causing said valve and said controlling means to be actuated in timed relation one to the other.

6. A device of the character described comprising a casing having a chamber provided with an inlet port communicating with a source of gas supply, said port having at its 125 inner end a valve seat, a valve to control

- said inlet port and having a screw-threaded stem, a screw-threaded support for said valve stem arranged within said chamber, said chamber also having an outlet, means 5 to control said outlet, and actuating means arranged exteriorly of said chamber to cause said valve and said controlling means to be actuated in timed relation one to the other.
10. 7. In a device of the character described, a casing having a chamber provided with an inlet port communicating with a source of gas supply, said inlet port having a tapered valve seat, a tapered valve co-operating with 15 said valve seat and having a stem, a support for said valve stem, said valve stem and said support having co-operating screw threads to impart longitudinal movement to said valve when said stem is rotated, an outlet passage leading from said chamber, a valve to control said passage and means for simultaneously actuating both of said valves, the movement of both valves in one direction being limited by the seating of the first 20 mentioned valve.
8. In a device of the character described, a casing having an inlet and outlet, valves to control said inlet and said outlet, a screw-threaded device for actuating one of said 25 valves and means for causing said valves to move in unison whereby the movement of both valves will be limited by the seating of that valve having the screw-threaded actuating device.
30. 9. In a device of the character described, a casing having an inlet and an outlet, a hollow valve member mounted in said casing communicating with said inlet and controlling said outlet, a tapered valve to control 35 said inlet, said tapered valve having a screw threaded stem and a support for said stem having a screw-threaded portion to co-operate with said stem, an operating member operatively connected with both of said 40 valves whereby said valves are moved in unison and their movement in one direction will be limited by the seating of said tapered valve.
45. 10. In a device of the character described, a casing having an inlet and an outlet, a screw actuated valve to control said inlet and a valve to control said outlet, and an operating device operatively connected with both of said valves.
11. In a device of the character described, 55 a casing having an inlet and an outlet, said inlet having a tapered valve seat, a screw actuated tapered valve adapted to control said inlet, a distributing valve to control said outlet, a shaft mounted in said casing 60 and connected with both of said valves and a handle to control the movement of said valve.
12. In a device of the character described, 65 a casing having an inlet and an outlet, said inlet having a tapered valve seat, a screw actuated tapered valve to control said inlet, a distributing valve to control said outlet, a shaft mounted in said casing, a connection between said shaft and said screw actuated valve to cause the latter to rotate with said shaft, but allowing it to have longitudinal movement relatively thereto, a connection between said shaft and said distributing valve to cause the same to rotate therewith and a handle for operating said shaft. 70
13. In a device of the character described, 75 a casing having an inlet and an outlet, a screw actuated valve to control said inlet, a distributing valve to control said outlet, a partition arranged between said inlet and said outlet and dividing said casing into two compartments, said partition having a port therein, a valve controlling the port in said partition, an operating device connected with each of said valves whereby a single movement of said operating device will 80 actuate each valve.
14. In a device of the character described, 85 a casing having an inlet and an outlet, a throttle valve to control said inlet and a distributing valve to control said outlet, said casing also having a supplemental outlet, and an actuating device, connections between said actuating device and the respective valves to cause said throttle valve to open before said distributing valve opens, thereby permitting said supplemental outlet to be connected with the inlet without 90 connecting the first mentioned outlet with 95 said inlet.
- In testimony whereof, I affix my signature in presence of two witnesses.
